UNITED STATES PATENT OFFICE.

ALLEN LOOMIS, OF ELKHART, INDIANA.

COMPOUND KEY MECHANISM FOR WOOD-WIND INSTRUMENTS.

Application filed November 2, 1925. Serial No. 66,185.

The present invention relates to musical instruments of the wood wind type, by which I mean instruments characterized by a tubular body, whether actually made of wood or metal, or some other material, within which is a column of air which makes a musical note when set in vibration, and lateral holes opening into the bore of the tube, adapted to be opened and closed for controlling the pitch of the emitted musical tone, and for other purposes. More particularly the invention is concerned with a key mechanism for controlling the tone holes of such instrument, such key mechanism being of the same general type as that of which several embodiments are illustrated in a patent application filed by me and entitled "Wood wind instruments," but involving a reversal in important particulars, and other modifications, from the key mechanisms there shown. The main object of the invention is to provide a mechanism of this character, involving a lever supported in a floating manner by a carrier, with which the cover or pad for a tone hole, and two or more finger operated keys are associated, said mechanism having in general the same advantages as ascribed to the floating lever key mechanism in my application aforesaid, and having special advantages of its own as appear hereinafter.

The mechanism here involved is applicable to wood wind instruments of different specific classes, including the flute, clarinet, oboe and saxophone. In the following description of the embodiment chosen for illustration here, I will explain its application and manner of use in connection with the G sharp tone hole of the E flat alto saxophone; making it understood, however, that this specific explanation is for illustration and convenience only, and without limiting intent. The same essential mechanism, having the same principles of operation and result may be applied to other tone holes of the saxophone, or to other wood wind instruments, with or without modification in the construction and arrangement of its several parts or of the combination as a whole.

In the drawings furnished herewith;

Figure 1 is a perspective view of the key mechanism embodying this invention as designed and applied for the specific use above mentioned; said figure showing also in a fragmentary manner the parts of the body

tube and bell, of the saxophone on which the mechanism is mounted;

Fig. 2 is a plan view of the key mechanism detached from the instrument and brought into substantially a single plane;

Fig. 3 is an end elevation of the mechanism as seen from the left of Fig. 2, the body tube and bell of the instrument being shown in section;

Fig. 4 is a cross section of the body tube and mechanism at the location of the line 4-4 of Fig. 2.

Like reference characters designate the same parts wherever they occur in all the figures.

Describing now for illustration the embodiment of this invention designed for use in a specific location on a saxophone, and referring to the drawings, the numeral 1 represents a fragment of the body tube of the instrument and 2 represents the adjacent part of the bell. 3 represents the tone hole cover or pad provided for the G sharp tone hole of this particular instrument. Said cover 3 is secured to a lever 4 pivoted on a pivot rod 5 which is supported from the body by posts or pillars 6 and 7. The lever has a hub sleeve 8 which surrounds the pivot rod and crosses the space between the two pillars. It also has a foot 9 adapted to bear on the body tube.

To the lever 4 there is pivoted by a pivot rod 10 a floating lever having the form of a substantially rectangular frame consisting of longitudinal or side bars 11 and 12 and transverse or end bars 13 and 14. Said bars are rigidly joined to one another in a unit structure. The side bar 11 is offset away from the body far enough to clear the cover 3 and the pivot 5, and permit the intended movements of both the lever and the cover, while the side bar 12 is offset laterally to clear the cover 3. A sleeve 15 is made fast to lever 4 and surrounds the pivot 10, occupying the space between the side bars 11 and 12. The lever 4 thus constitutes a carrier for this frame or floating lever. A flat spring 16 is secured at one end by a screw 17, to the end of the side bar 12, and its free end bears on a reaction pin 18 projecting from the side of the carrier lever 4. The action and reaction of the spring, exerted on the carrier and floating lever, normally hold the foot 9 of the carrier lever against the body tube and raise the end 13

of the floating lever into contact with the arm 22 which will presently be described.

A finger key 19, in this instance the key for the third finger of the left hand, is carried by an arm 20 which is connected by a bridge rod 21 with an arm 22 secured to a sleeve 23 surrounding a pivot rod 24. Said pivot rod extends longitudinally of the body tube, being supported on a series of posts 10 or pillars of which three are shown in the drawings, and are designated 25, 26, and 27. This rod is also the support for a number of other keys and arms, not shown in this drawing, with which the instrument is 15 equipped. The arm 22 overlies the bar 13 of the floating lever and serves as a means for depressing the upper end of the floating lever and closing the cover 3. The lift of the arm 22 is limited by the octave mechanism. 20

A second finger key 28, which in this instance is adapted to be depressed by the little finger of the left hand, is carried by an arm 29 secured to a bridge rod 30, which 25 latter is carried by arms 31 and 32 having their bearing on a pivot rod 33, which is supported from the body tube by posts or pillars 34 and 35 and others, and serves also as the pivotal support for other keys 30 of the instrument, not shown herein. The arm 32 extends across the pivot rod and carries a roller 36, or equivalent projection or finger, which bears on one arm 37 of a two-armed lever secured to a sleeve 38 mounted 35 to turn about a third longitudinal pivot rod 39 which is supported by posts 40 and 41 from the instrument body. The second arm 42 of the two-armed lever above mentioned overlies the bar 14 of the floating lever. A 40 needle spring 43 is mounted in the post 41 and engages a hook 44 on the under side of the arm 37, exerting a downward force through the arm 42 on the floating lever and normally depressing the lower end bar 14 45 to the extent permitted by a fixed stop knob 42^a, against which arm 42 bears. The arm 42 is normally in contact with this stop knob, which limits the depression of the bar 14 to the amount necessary to enable the 50 stopper to be closed when key 19 is fully depressed.

A third finger key 45, which is a special key for the first finger of the right hand, is carried by an arm 46 secured to a sleeve 47 which has rotative bearing on a pivot rod 48 supported from the bell 2 by posts 49 and 50. To the sleeve 47 is secured another arm 51 which extends between the body tube and a projection 52 on the bridge rod 30. 55 The mounting of these arms from the bell is a convenient mode of supporting them clear of other mechanisms. Their relation to the body tube, as to their rising and descending movements, however, is similar to that 60 of the other arms and keys. A needle spring 65

53 is mounted in the post 49 and engages with a hook 54 on the sleeve 47 and tends to raise key 45 and depress arm 51, such movement being stopped by engagement of arm 51 with sleeve 38. The bridge rod 30 carries a foot piece 55 which bears on the body tube and so limits rise of the finger key 28.

The tone hole cover 56 next below the cover 3, that for the G natural hole, carries 75 an arm 57 which overlies the bar 14 of the floating lever. The cover 56 is so engaged with a finger key 58 on the cover 59 for the F sharp hole that when key 58 is depressed the cover 56 also is depressed and arm 57 is 80 held down upon the lower end of the floating lever. While the precise mode of effecting such engagement between the F sharp and G natural covers is not material to this invention, I have shown diagrammatically 85 in Figure 2 the means by which such engagement is accomplished in the saxophone here illustrated. The cover 56 is secured to an arm 60 having a sleeve 61 which rotates about the pivot rod 39, and the cover 59 is 90 secured to an arm 62 having a sleeve 63 which turns about the same pivot rod. A bent arm 64 secured to sleeve 63 passes under an arm 65 secured to the sleeve 61, and thereby depression of key 58 causes 95 both covers 59 and 56 to be depressed. Springs of ordinary character applied in ways well understood to those acquainted with the art, normally lift the covers 56 and 59, and hold them in raised position. 100

It will now be understood that when the finger key 19 is depressed, the cover 3 is closed. The A natural tone hole cover is likewise closed by depression of key 19 through a simple connection from the sleeve 105 23, not necessary to be described here. While key 19 is held down, the key 28 may be pressed upon, with the effect of raising arm 42 and releasing the lower end of the floating lever. The spring 16 then becomes 110 effective to raise this end of the floating lever and again open the stopper. The same effect may be obtained by depressing finger key 45 which, by acting through the arm 51 and projection 52 causes the arm 32 to act 115 on lever 37-42 in the same manner as when key 28 is depressed.

The result of closing cover 3 by depression of key 19, and then opening it by depression of key 28 or 45, follows from the 120 fact that the spring 43 exerts a stronger depressing pressure on the lower end of the floating lever than the lifting pressure thereon which is exerted by spring 16 when the upper end of the floating lever is depressed. 125 When both ends of this lever are left free and unconstrained, the effect of spring 16 is to depress the lower end of the floating lever, acting thus through the reaction of the foot of the carrier lever 4 on the body tube. 130

When the upper end of the floating lever is depressed, and its lower end left unconstrained, the spring 16, reacting against the depressing force, raises the lower end of the floating lever. The force thus exerted by the spring 16 to raise the lower end of the floating lever under such conditions is weaker than the force exerted by spring 43 tending to lower it; whereby the spring 16 is overcome and the cover 3 closed when key 19 is pressed and arm 42 remains depressed by its spring, but acts to raise the cover when the constraint exerted by spring through arm 42 is removed; but the cover 3 remains open if either key 28 or 45 is depressed before or simultaneously with depression of key 19.

When keys 19 and 28 or 45 are simultaneously depressed, the cover 3 can be closed and opened simultaneously with covers 56 and 59 by pressing and releasing key 58. This is one of the advantages of the present invention as applied to the saxophone, that the trill from F natural to G sharp may be played by vibrating the right forefinger only, while the keys 19 and 28 are held down by the third and fourth fingers of the left hand.

The G sharp floating lever mechanism here described embodies the principles of a floating lever coasting through its carrier upon a hole cover or key, a single spring between said carrier and floating lever normally raising one arm of the floating lever and raising the cover, and acting to raise the cover and the opposite end of the floating lever when the first end is depressed; combined with a spring normally depressing one arm of the floating lever, a key for removing the restraint exerted by the last named spring; and a third key effective to apply pressure to the same end of the floating lever when such restraint is removed.

The pressure exerted by the arm 57, or its equivalent, on the floating lever may be applied to the upper end of the floating lever, rather than to its lower end in the manner here shown; and other rearrangements and modifications in the keys by which the floating lever mechanism is controlled may likewise be made within the spirit of this invention. It is not at all important in the broad sense which digits respectively close and open the stopper, nor which finger key acts on the upper end and which on the lower end of the floating lever, nor which end of the floating lever is arranged toward the upper or lower end of the instrument.

This character of floating lever, constructed as a frame with transverse bars at its ends, is extremely strong and rigid, and gives plenty of room for applying a diversity of pressers at either end. Two pressers, the arms 42 and 57, are here shown applied to one of the end bars, and there is room for

additional pressers to be there applied, if needed; and additional pressers could readily be applied to the bar 13 by displacing to one side or the other all of the arm 22 except only that part which bears on the bar. 70

It may be noted that the key 19 is the key which controls the lower octave hole, as described in my companion application for "triple automatic octave mechanism" herein identified. 75

In the foregoing description the terms "depress," "lower," and words of similar import, when applied with reference to the motions and force imposed on the key mechanisms and parts thereof, signify movement 80 or force directed toward the body of the instrument, whatever may be the relation of such directions to the horizontal; while the terms "lift," "raise," and terms of similar import, signify directions away from the 85 body, without reference to the relation of these directions to the horizontal. The terms defined above have no relation to the terms "upper" and "lower" as applied to the opposite ends or arms of the floating 90 lever and to the longitudinal arrangement of different keys and stoppers; since the latter terms refer to the relation to and distances from the mouth end or the foot end of the instrument. In this sense "upper" 95 means nearer to the mouth end and "lower" means nearer to the foot end of the instrument in the direction of the ascending and descending scale of notes.

I claim:

1. In a wood wind instrument a key mechanism comprising a pivoted operated member, a floating lever pivoted to said member, a spring mounted on said lever and acting on said member to raise both said member and one arm of the floating lever, and separate operating members arranged to apply pressure with depressing effect to opposite arms of said floating lever. 100

2. In a wood wind instrument a key mechanism comprising a pivoted operated member, a floating lever pivoted to said member, a spring mounted on said lever and acting on said member to raise both said member and one arm of the floating lever, and separate operating members arranged to apply pressure with depressing effect to opposite arms of said floating lever, one of said operating members being spring actuated to apply such pressure and digit operated to relieve the pressure. 110

3. In a wood wind instrument a key mechanism comprising a pivoted operated member, a floating lever pivoted to said member, a spring mounted on said lever and acting on said member to raise both said member and one arm of the floating lever, and separate operating members arranged to apply pressure with depressing effect to opposite arms of said floating lever, one of 120

said operating members being digit actuated to apply such pressure.

4. In a wood wind instrument a key mechanism comprising a pivoted operated member, a floating lever pivoted to said member, a spring mounted on said lever and acting on said member to raise both said member and one arm of the floating lever, and separate operating members arranged to apply pressure with depressing effect to opposite arms of said floating lever, one of said members being spring actuated, and the other being digit actuated to apply said pressure, and the spring actuated member being operable by pressure of a digit to overcome such spring pressure.

5. In a wood wind instrument a key mechanism comprising a lever pivotally supported from the body of the instrument, a floating lever pivoted to the before named lever, a spring secured to one of said levers and pressing upon the other with tendency to raise one arm of each and to press the other arm of one against the instrument body, and operating members arranged to apply pressure with depressing effect to the arms of said floating lever.

6. In a wood wind instrument a key mechanism comprising a lever pivotally supported from the instrument body and having a foot adapted to bear on said body, a floating lever pivoted to the before named lever, a spring reacting between said levers and normally pressing the above specified parts of the first-named lever against the body and raising one arm of the floating lever, and digit controlled means for depressing the arms of said floating lever.

7. In a wood wind instrument a key mechanism comprising a stopper-carrying lever pivoted to the body of the instrument, a floating lever pivoted to the stopper-carrying lever at one side of the pivot of the latter, a spring secured to one of said levers and reacting against the other tending to hold the stopper raised and the adjacent end of the floating lever depressed, and digit controlled means for pressing on the opposite end of said floating lever; the spring being arranged to act on the floating lever adjacent to said opposite end, whereby it permits depression thereof without depressing the stopper when the before mentioned depressed end of the lever is free to rise.

8. In a wood wind instrument a key mechanism comprising a stopper-carrying lever pivoted to the body of the instrument, a floating lever pivoted to the stopper-carrying lever at one side of the pivot of the latter, a spring secured to one of said levers and reacting against the other tending to hold the stopper raised and the adjacent end of the floating lever depressed, digit controlled means for pressing on the opposite

end of said floating lever; said spring being arranged to permit depression of said opposite end without depressing the stopper when the before mentioned depressed end of the lever is free to rise, a spring normally exerting restraint on the said depressed end of said floating lever, and a digit operated means for removing the restraint of said last named spring.

9. In a wood wind instrument a stopper-carrying lever pivotally supported from the body of the instrument, a floating lever constructed as a frame having side bars and end bars rigidly connected together, the side bars of said floating lever frame being arranged to embrace the stopper carrying lever and pivoted thereto, and digit controlled operating arms overlying and adapted to bear against the end bars of said frame.

10. A key mechanism for wood wind instruments comprising a carrier lever pivotally supported from the body of the instrument, a hole cover secured to said lever, a floating lever pivotally supported by said carrier lever, a spring secured to said floating lever and bearing against said carrier lever with tendency to raise the cover and one end of the floating lever, the other end of both the carrier lever and the floating lever reacting against the instrument body, a digit operated lever for depressing the normally raised end of the floating lever and a digit controlled arm for applying depressing pressure on the normally depressed end of said floating lever.

11. A key mechanism for wood wind instruments comprising a carrier lever pivotally supported from the body of the instrument, a hole cover secured to said lever, a floating lever pivotally supported by said carrier lever, a spring secured to said floating lever and bearing against said carrier lever with tendency to raise the cover and one end of the floating lever, the other end of the carrier lever reacting against the instrument body, a digit operated lever for depressing the normally raised end of the floating lever and a digit controlled arm for applying depressing pressure on the normally depressed end of said floating lever.

12. In a wood wind instrument a pivotally mounted stopper-carrying lever, a floating lever pivoted to said stopper-carrying lever, a spring acting between said levers normally raising the stopper carrying arm of the first lever and one end of the floating lever, a spring pressed arm normally depressing the opposite end of said floating

- lever, a digit operated arm for depressing the normally raised end of the floating lever, and a digit operated key for overcoming the effect of said spring pressed arm; the before 5 named spring being then effective to raise the stopper and the normally depressed end of the floating lever, provided the normally raised end of said lever is pressed upon at the same time.
- 10 13. In a wood wind instrument a pivotally mounted stopper-carrying lever, a floating lever pivoted to said stopper-carrying lever, a spring acting between said levers normally raising the stopper-carrying arm 15 of the first lever and one end of the floating lever, a spring pressed arm normally depressing the opposite end of said floating lever, a digit operated arm for depressing the normally raised end of the floating lever, 20 a digit operated key for overcoming the effect of said spring pressed arm, the before named spring being then effective to raise the stopper and the normally depressed end of the floating lever provided the normally 25 raised end of said lever is pressed upon at the same time, and a digit operated key mechanism for depressing the normally depressed but now raised end of the floating lever.
- 30 14. In a wood wind instrument a pivotally mounted carrier lever, a hole stopper secured to one arm of said lever, a floating lever pivoted to said carrier lever at one side of the pivot of the latter, a spring acting 35 between said levers normally raising the stopper holding arm of the carrier lever and one arm of the floating lever, and adapted to raise the other arm of said floating lever when the normally raised arm is depressed, 40 a spring pressed arm normally bearing on one arm of the floating lever, a digit operated arm for pressing on the other arm of said floating lever, a digit operated mechanism for overcoming the pressure of said
- spring pressed arm on the floating lever, and 45 digit operated mechanism for depressing the arm of the floating lever on which said spring pressed arm bears, when the pressure of the latter is released.
15. In a wood wind instrument a tone hole 50 stopper, a floating lever pivotally connected with said stopper, a spring acting between said stopper and floating lever normally opening the stopper and raising one arm of the floating lever, said floating lever being 55 arranged to close the stopper when both of its arms are depressed and to permit opening of the stopper whenever one arm alone is depressed, a spring normally depressing one arm of the floating lever, a key for depressing the other arm of said lever, a second key for removing the pressure of said last named spring, and a key for depressing the first named arm of the floating lever 60 when the pressure of the second named 65 spring is released.
16. In a saxophone a tone hole stopper, a spring normally opening said stopper, a key and a second spring operating in conjunction to close the stopper, a second key 70 for overcoming the second named spring, whereby the stopper is opened when both said keys are pressed upon, and a third key for closing the stopper when the two before named keys are simultaneously depressed. 75
17. In a saxophone a tone hole cover, a spring normally opening said cover, a key and a spring cooperating to close the cover, a second key for opening the cover while the first key is pressed upon, and a connection from an adjacent hole cover for closing the previously named hole cover 80 when both keys are pressed upon simultaneously.
- In testimony whereof I have affixed my 85 signature.

ALLEN LOOMIS.
